Primary Examiner — Paula Allen Greene(74) *Attorney, Agent, or Firm* — QuickPatents; Kevin Prince(57) **CLAIM**

The ornamental design for a motorcycle engine urn, as shown and described.

DESCRIPTION

FIG. 1 is a perspective view of a motorcycle engine urn showing my new design;

FIG. 2 is an exploded perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof; and,

FIG. 7 is a bottom plan view thereof.

1 Claim, 7 Drawing Sheets(56)
